UNITED STATES PATENT OFFICE.

MARK W. MARSDEN, OF PHILADELPHIA, PENNSYLVANIA.

COTTON-GIN.

1,192,660.

Specification of Letters Patent. Patented July 25, 1916.

Application filed May 19, 1915. Serial No. 29,155.

To all whom it may concern:

Be it known that I, MARK W. MARSDEN, a citizen of the United States, residing at Philadelphia, in the county of Philadelphia and State of Pennsylvania, have invented 5 certain new and useful Improvements in Cotton-Gins, of which the following is a specification.

The prior art is constituted of many 10 types of gins, but the saw.gin has come to be recognized as the best exemplification of this class of apparatus and is the type in most common use today. Yet the saw gin presents to those skilled in the art defects 15 which heretofore have not been overcome. Principal among these is the fact that it is wasteful and hence low in efficiency. This is due to the destructive action of the saws, which rip and tear the staple and at the 20 same time leave considerable short staple adhering to the seeds so that further so-called denuding operations are required to remove the short staple and lint from the seeds.

25 Objects of the present invention are to provide for rapidly and thoroughly ginning cotton; to provide for ginning even to the extent of denuding the seeds; to provide a machine of simple construction, yet capable of treating a relatively large quantity 30 of cotton without cutting, breaking or otherwise injuring the fiber; and to provide a comparatively compact gin, which is economical to run and is susceptible of being 35 made of very large capacity.

Generally stated, the invention contemplates subjecting the seed cotton to the action of confronting and comparatively flat ginning devices, which exert an opposite 40 pull on the cotton without liability of tearing or breaking the fiber whereby it is repeatedly turned or rolled so as to expose all parts of the same to the action of the ginning devices until it is thoroughly divested 45 of seed and other extraneous matter and is finally delivered from the machine in perfect condition.

Further stated, the invention embodies 50 confronting ginning aprons between which the seed cotton is operated on and the action of which is to straighten out and dis-

entangle the fibers and thus loosen and separate the seeds and dirt as distinguished from the ripping or tearing action of a saw gin.

More specifically stated, the invention embodies a pair of co-operating ginning aprons, 55 means for relatively adjusting them, means for delivering cotton to the aprons, means for driving the aprons in opposite directions and if desired at relatively different speeds, 60 stripping mechanism, and means for removing the ginned cotton from the aprons.

The nature, characteristic features and scope of the invention will more readily be understood from the following description 65 and claims taken in connection with the accompanying drawings, forming a part hereof, wherein—

Figure 1 is a top view of a machine embodying features of my invention. Fig. 2 70 is a vertical sectional view of the same. Fig. 3 is a fragmentary view in perspective of an apron and stripper showing the relative arrangement of the same. Fig. 4 is a vertical sectional view of a modified type of 75 machine. Fig. 5 is a detail showing one method of securing the ginning teeth to the aprons. Fig. 6 is a perspective view of a preferred type of ginning teeth. Fig. 7 is a sectional view of a modification in which 80 suction flues are provided to take care of the ginned cotton. Fig. 8 is an elevational view of the machine, more particularly showing the driving mechanism. Fig. 9 is a perspective view of one of the aprons and 85 its rolling abutment. Fig. 10 is a perspective view showing the staggered arrangement of the opposed teeth.

Referring to the drawings, the numeral 5 designates a framework of suitable construction, 90 which supports the various elements of the machine.

6 and 7 indicate endless belts or aprons disposed somewhat out of the perpendicular and which are comparatively close together 95 at the bottom or seed outlet end of the machine and which diverge at the top where they may extend well up to the seed cotton hopper 8 so as to form practically a prolongation of said hopper. The aprons 6 and 100 7 are so disposed and equipped that when operated as hereinafter described they con-

stitute devices for opening, combing or dis-
5 entangling, cleaning, ginning and delinting
the material under treatment. The aprons
are adapted and arranged to be driven in re-
verse directions and, if desired, at different
10 speeds relatively and they are adjustable
with relation to each other. Each of said
aprongs is formed of canvas, leather, or other
appropriate material on the underside of
15 which are secured in any suitable way means
such as the slats or bars 9, which range
transversely of the aprons and are spaced
apart to form intervals between them and
serve to support the ginning teeth.
20 As shown in Fig. 6, the preferred type of
teeth is a slightly curved, tapered and pointed
member 10 having a threaded stock 11, which
penetrates the slat and apron and is
retained by a nut 12 that is inset in the slat
25 in order to constitute no obstruction. The
provision of the slats is an effective way of
securing precise adjustment or accurate
alinement of the teeth for it is essential that
the teeth be disposed uniformly; and the
30 particular type of retaining means referred
to is advantageous in the event it becomes
necessary to remove and replace any one or
more of the teeth. The slats or bars 9 are
mutually spaced or have like intervals be-
35 tween them and constitute teeth or sprockets,
which engage with upper and lower sprocket
wheels or corrugated rollers 13 and thereby
impart the desired movements to the aprons.
The apron supports or corrugated rollers 13
40 are mounted in bearings 14 of well known
design and construction and the nature of
which is such as will enable them to be
shifted so as to vary the degree of inclina-
tion of the aprons to regulate the feed. The
45 bearings 14 also permit the aprons and apron
supports to be shifted so as to take up slack
of the aprons it being desirable at all times
to have the aprons as tightly stretched as
possible. The teeth carrying slats or sprock-
50 etts may also engage toothed idlers or rolling
abutments 15, which when present operate
to maintain a flat or stretched condition of
the respective aprons particularly on the
hopper or cottonward side. Otherwise stat-
55 ed, the provision of the idlers operates to
prevent deformation of the aprons so that
the alinement of the ginning devices is pre-
served and they are held well up to their
work. The idlers are mounted in adjustable
60 bearings 16 and may be shifted in response
to adjustments of the aprons through the
medium of hand wheels 17.

The apron 6 is arranged to be driven in
a downward direction and its teeth on the
65 down side are directed downwardly, which
is the reverse of the teeth on the upwardly
driven apron 7. Thus in passing the upper
sprocket roller the apron 6 operates to pull
cotton from the hopper 8 and in this respect
it may be termed a self-feeder. The aprons

with relation to their teeth are out of aline-
ment, see Fig. 10, so that the teeth are en-
abled to pass each other freely. Each apron
cooperates with a ginning rib, consisting as
70 shown in Fig. 3 of a comb-like doctor or
member 18 curved to conform to the turns or
take-off ends of the aprons and with its tines
19 so disposed as to permit the free passage
between them of the apron teeth. The gin-
ning ribs are located, respectively, at the
75 bottom and top of aprons 6 and 7.

In practice, cotton is delivered to the V
shape space between the aprons where
through the action of the reversely trav-
eling aprons it is subjected to pulling in op-
posite directions so as to be opened up, freed
80 from leaves and dirt, and finally through
the intervention of the ginning ribs liber-
ated from the seeds, which latter together
with foreign substances are discharged
85 through a seed outlet 20. The ginned cot-
ton passes to adjustable rotary dosing or
brush cylinders 21, one for each apron, and
these devices operate to relieve the aprons of
the ginned cotton and to deliver it in the
90 form of a bat onto endless belts or convey-
ers 22. To aid in the bat formation any
suitable condensing means may be employed,
for example the condensing rolls 23. The
fact that the aprons are mutually opposed
95 or are driven in opposite directions and at
variable speeds greatly facilitates the open-
ing up or fiber straightening and loosening
process as well as the ginning and cleaning
process. It is not essential in all cases that
100 the aprons be driven at relatively different
speeds and the operation of the machine
with respect to this as well as the spacing
of the aprons or the adjustment of their
angle of inclination will be governed to some
105 extent by the condition of or the grade of
cotton to be ginned.

In Fig. 2, the upwardly traveling apron 7
is almost perpendicular, and the brush or
take-off cylinders 21 are located in proxim-
110 ity one with the top of apron 7 and the other
with the bottom of apron 6. In Fig. 4 the
angle of inclination is substantially alike
and both brush cylinders are located at the
top. The seeds and dirt are directed to a
115 suitable outlet 20, which may if desired be
equipped with a gate or valve 24, which
when present operates to retain the seeds
until they are thoroughly denuded of lint
and staple. To insure a uniform and con-
120 stant feed of cotton to the aprons, the hop-
per 8 may be provided with co-operating feed
rolls 25 equipped with teeth 26 and whereof
the bearings 27 are adjustable in the well
known manner so that the rolls may be
125 shifted in accordance with adjustments of
the ginning ribs and aprons. Manifestly
there are many forms of feed adapted to the
purpose and by way of illustration Fig. 4
shows an arrangement in which an endless
130

belt or conveyer 28 is substituted for the rolls 25.

The machine may be operated in any suitable manner. For example, as will appear in Figs. 1 and 2, the shaft of the upper roll of apron 7 is provided with a belt pulley 29 driven by a belt 30. On the opposite side of the machine the same shaft is provided with a gear wheel 31 connected by a chain 10 drive 32 with a gear wheel 33 on the upper roll of apron 6. Obviously a variation in the sizes of these gears will provide for the desired differential speed of the aprons. From the last named roll the feed devices are 15 operated by a chain drive 34 and crossed belt 35. The brush cylinder of apron 6 is driven by a cross belt 36 and in turn drives the conveyer 22. The brush cylinder of apron 7 is 20 driven by a crossed belt 37 and in turn drives its complementary conveyer. For balancing purposes the lower roll of apron 7 is provided with a flywheel 38.

The aprons, ginning ribs and other operating parts are preferably housed within a casting 39 of any suitable construction such as 25 will admit of ready accessibility to the various operating elements for inspection or repairs. In Fig. 8, the brush cylinders are 30 equipped with hoods 40, having regulating dampers 41.

It will be obvious to those skilled in the art to which the invention relates that modifications may be made in details without departing from the spirit and scope of the invention. Hence the same is not limited 35 other than required by the state of the prior art.

Having described the nature and objects of the invention, I claim:—

40 1. In a machine of the type recited, the combination of confronting upwardly ranging aprons whereof each is equipped with ginning teeth, ginning members coöperating with the aprons, rotary supports for the aprons, and means for adjusting them to provide a V shape feed space between the aprons.

2. In a machine of the type recited, the combination of V spaced confronting aprons, 50 ginning teeth detachably applied to the aprons, ginning members coöperating with the aprons, apron supports, and means for driving them.

3. In a machine of the type recited, the 55 combination of confronting upwardly ranging aprons whereof each is equipped with ginning devices, ginning members coöperating with the apron, rotary supports for the aprons, means for adjusting them to provide a V shape feed space between the aprons, and a feed hopper above the apron.

4. In a machine of the type recited, the 60 combination of V spaced confronting aprons, ginning teeth detachably applied to the aprons, ginning members coöperating with

the aprons, apron supports and means for driving them, and a feed hopper above the aprons and co-extensive with the V space.

5. In a machine of the type recited, the combination of upstanding traveling aprons 70 equipped with coöperative ginning teeth, means for feeding seed cotton downwardly between the aprons, a ginning rib at the take-off end of each apron, and doffing mechanism for the aprons. 75

6. In a machine of the type recited, the combination of V spaced confronting aprons equipped with coöperative ginning devices, the wide end constituting a seed cotton inlet and the other end constituting a seed outlet, 80 means for driving the aprons in opposite directions, and take-off mechanism operatively disposed with respect to the aprons.

7. In a machine of the type recited, the combination of V spaced ginning aprons, 85 means for effecting relative adjustments thereof to regulate the space, means for feeding seed cotton to the aprons, ginning members co-operating with the aprons, and means coöperating with the aprons for delivering the ginned cotton in the form of a bat. 90

8. In a machine of the type recited, the combination of upstanding traveling aprons equipped with coöperative ginning teeth, 95 means for feeding seed cotton downwardly between the aprons, a curved ginning rib at the take-off end of each apron, and doffing mechanism for the aprons.

9. In a machine of the type recited, the 100 combination of upwardly diverging aprons provided with coöperative ginning devices, means for driving them, means for adjusting the aprons to regulate the space between them, and a feed hopper above and co-extensive with the space between the aprons and capable of adapting itself to adjustments of the aprons. 105

10. In a machine of the type recited, the combination of upwardly diverging aprons 110 provided with coöperative ginning devices, means for driving them in opposite directions, means for adjusting the aprons to regulate the space between them, and a feed hopper above and co-extensive with the 115 space between the aprons and capable of adapting itself to adjustments of the aprons.

11. In a machine of the type recited, the combination of inclined ginning aprons, 120 means for effecting relative adjustments thereof, means for supplying seed cotton to the aprons, ginning members coöperating with the apron, and means for removing the ginned cotton.

12. In a machine of the type recited, the 125 combination of upwardly diverging aprons, means for effecting relative adjustments thereof, ginning teeth carried by the aprons, means for driving the aprons, means for feeding seed cotton to the aprons, a ginning 130

rib at the take-off end of each apron, and means for removing the ginned cotton.

13. In a machine of the type recited, the combination of upwardly diverging ginning aprons, means for driving them in opposite directions, means for feeding cotton downwardly between them, ginning ribs coöperating with the aprons, and means for removing the ginned cotton.

14. In a machine of the type recited, the combination of V spaced aprons equipped with coöperative ginning devices, means for adjusting the aprons to regulate said space, means for feeding seed cotton downwardly between the aprons, and means for driving the aprons in opposite directions and at differential speeds.

15. In a machine of the type recited, the combination of a pair of upwardly diverging ginning aprons, means for driving them in opposite directions and one faster than the other, means for feeding seed cotton to the space between the aprons, a ginning rib for each apron, and means for effecting relative adjustments of the aprons and ginning ribs.

16. In a machine of the type recited, the combination of a pair of traveling aprons equipped with ginning devices and whereof the arrangement is such that the aprons are close together at one end and divergent at the other, and means for supplying cotton to the space between the aprons.

17. In a machine of the type recited, the combination of a pair of traveling aprons equipped with ginning devices and whereof the arrangement is such that the aprons are close together at one end with provision for said devices to clear each other and comparatively widely divergent at the other end, means for feeding cotton to the wide end, and means for driving the aprons in opposite directions.

18. In a machine of the type recited, the combination of a pair of traveling aprons equipped with reversely disposed ginning devices and whereof the arrangement is such that the aprons are relatively close together at one end and widely divergent at the other end, and means for feeding cotton to the wide end.

19. In a machine of the type recited, the combination of a pair of relatively adjustable traveling aprons equipped with ginning devices and whereof the arrangement is such that the aprons are relatively close together at one end and divergent at the other, means for feeding cotton to the space between the aprons, and means for driving the aprons in opposite directions.

20. In a machine of the type recited, the combination with the ginning aprons and means for driving them, of means to prevent deformation of the aprons.

21. In a machine of the type, recited, the

combination with the adjustable aprons and apron rolls, of rolling abutments intermediate the rolls and bearing against the aprons to prevent deformation of the aprons, and means for adjusting them in response to adjustments of the aprons.

22. In a machine of the type recited, the combination of a pair of upwardly diverging ginning aprons, means for driving them in opposite directions and one faster than the other, seed cotton supply provisions at the upper ends of the aprons and a seed outlet provision at the lower ends thereof, a curved ginning rib for each apron, and means for effecting relative adjustments of the aprons and ginning ribs.

23. In a machine of the type recited, the combination with the apron supports, of aprons having slats designed to engage the apron supports and equipped with ginning devices.

24. In a machine of the type recited, the combination with the apron supports, of aprons having slats designed to engage the apron supports, and ginning teeth detachably secured to the slats.

25. In a machine of the type recited, the combination of confronting ginning aprons, means for driving them in opposite directions, teeth detachably secured to the aprons, the opposed teeth being out of alinement so as to clear each other, and a ginning rib at the takeoff end of each apron.

26. In a machine of the type recited, the combination of confronting ginning aprons, means for driving them in opposite directions, teeth detachably secured to the aprons, the opposed teeth being out of alinement so as to clear each other, a ginning rib at the take-off end of each apron, and a valved seed outlet for the aprons.

27. In a machine of the type recited, the combination of a pair of coöperating ginning aprons, apron supports, means for driving them in opposite directions and one faster than the other, and a balance wheel on one of the supports of the low speed apron.

28. In a machine of the type recited, the combination of mated confronting ginning aprons equipped with reversely disposed teeth, means for driving the aprons in opposite directions and at different relative speeds, and independent ginning ribs and deflating mechanism for each apron.

29. In a machine of the type recited, the combination of mated ginning aprons equipped with reversely disposed teeth, means for adjusting the aprons to regulate the feed, means for driving them in opposite directions, a curved ginning rib at the take-off end of each apron, and means for adjusting the ribs in accordance with adjustments of the aprons.

30. In a machine of the type recited, the

combination of confronting ginning aprons with an open space or feed end, a feed hopper in operative relation therewith, means for adjusting the aprons to regulate the feed, means for driving them in opposite directions, and independent ginning rib and doffing mechanism for each apron.

In testimony whereof I affix my signature in presence of two witnesses.

MARK W. MARSDEN.
